UNITED STATES PATENT OFFICE

153,848

DESIGN FOR A TANK TRUCK

Theodore G. Branham, North Kansas City, Mo.,
assignor to Standard Steel Works, North Kan-
sas City, Mo., a corporation of Missouri

Application April 24, 1946, Serial No. 128,911

Term of patent 7 years

(Cl. D14—3)

To all whom it may concern:

Be it known that I, Theodore G. Branham, a citizen of the United States, residing at North Kansas City, in the county of Clay and State of Missouri, have invented a new, original, and ornamental Design for Tank Truck, of which the following is the specification, reference being had to the accompanying drawing, forming part thereof.

Fig. 1 is a side elevational view of a tank truck showing my new design.

Fig. 2 is a rear end view of the tank truck.

Fig. 3 is a plan view of the front portion of the tank truck.

I claim:

The ornamental design for a tank truck, as shown.

THEODORE G. BRANHAM.
